UNITED STATES PATENT OFFICE

ANSON SEARLS, OF NEWARK, NEW JERSEY.

DESIGN FOR BACK CROSS-STRAP MOUNTINGS FOR CARRIAGES.

Specification forming part of Design No. 6,592, dated April 15, 1873; application filed January 8, 1873.

To all whom it may concern:

Be it known that I, ANSON SEARLS, of Newark, New Jersey, have invented and produced a new and original Design for Back Cross-Straps and Ornaments for Carriages, of which the following is a specification:

The nature of my design consists in the shield-form of the buckle, made substantially in the form shown in the accompanying photographic illustration, and in the grand center-piece, when made to represent a series of shield forms radiating from a common center.

The buckles are shield-form, having a square opening in the center, the metal being raised a certain distance from said opening and then beveled, or being on an incline to the outside, as shown. The center-piece is formed by

having a square in the center, from which the shield-forms branch off; and each of said forms has an open shield-form in its center, as shown. The center-piece and buckles, of the form described and illustrated, are arranged with straps, as shown, to form the design for back cross-straps.

What I claim, and desire to secure by Letters Patent, is—

1. The design for center-piece, as shown and described.
2. The design for back cross-strap, as shown and described.

ANSON SEARLS.
